UNITED STATES PATENT OFFICE.

THOMAS G. HAWKES, OF CORNING, NEW YORK.

DESIGN FOR THE ORNAMENTATION OF GLASS, &c.

SPECIFICATION forming part of Design No. 17,838, dated October 25, 1887.

Application filed August 31, 1887. Serial No. 248,422. Term of patent 3½ years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying photograph, forming part thereof.

10 I show my design applied as an ornament to a glass globe or finger-bowl.

It consists of a series of rosettes, 1, increasing in size from the base to the top, a series of small rosettes, 2, in the spaces left by the large rosettes, a rounded projection, 3, above each series of the large rosette portions, upwardly-extending plain ribs or pillars 4 on each side of the rosette portions, having rounded projec-

tions 5, and beads 6 between the ribs or pillars, having transverse recesses 7 and pointed projection 8.

Having thus described my design, the following is what I claim as new therein and desire to secure by Letters Patent:

The design for the ornamentation of glass and other ware herein shown and described, the same consisting of a series of rosettes, series of small rosettes in the spaces left by the larger rosettes, ribs or pillars on each side of the rosette portions, and a bead between the ribs or pillars, having transverse recesses.

THOMAS G. HAWKES.
